UNITED STATES PATENT OFFICE

JOHN F. O'CONNOR, OF CHICAGO, ILLINOIS, ASSIGNOR TO W. H. MINER, INC., OF CHICAGO, ILLINOIS, A CORPORATION OF DELAWARE

RAILWAY DRAFT RIGGING

Application filed February 16, 1931. Serial No. 516,041.

This invention relates to improvements in railway draft riggings.

One object of the invention is to provide a railway draft rigging including a shock absorbing mechanism which is compressed to a greater extent in buff than in draft to provide correspondingly higher shock absorbing capacity, wherein the shock absorbing mechanism comprises a friction shell and cooperating friction elements, and the compression thereof in draft is limited by stop means in the form of relatively heavy keys secured to the underframe structure of the car and having shouldered engagement with the shell 15 of the shock absorbing mechanism, and the compression in buff is limited by engagement of the usual main follower with the corresponding end of the friction shell.

Another object of the invention is to provide a railway draft rigging of the character indicated in the preceding paragraph, wherein the stop keys also serve to support and guide one end of the friction shell while the other end thereof is supported by a saddle 25 plate member.

Other objects of the invention will more clearly appear from the description and claims hereinafter following.

In the drawing, forming a part of this specification, Figure 1 is a horizontal, longitudinal, sectional view through the underframe structure of a railway car, illustrating my improvements in connection therewith, and Figure 2 is a longitudinal side elevational view of the structure illustrated in Figure 1.

In said drawing, 10-10 indicates channel shaped center or draft sills of the underframe structure of a railway car. The usual striking casting 12 is fixed to the outer ends of the sills and has front stop members 13-13 formed integral therewith. As shown, the front stop members have aligned coupler key guide slots 14-14 therein. The sills 10-10 have their outer ends disposed inwardly of the outer face of the striking casting 12, and the sills are provided with openings at the forward ends which receive the usual flanges surrounding the guide slots 14 of the stop members 13-13. A combined rear stop and

filler casting 15 is fixed between the draft sills, said casting being recessed as indicated at 16 to accommodate the rear end portion of the yoke. A carry iron member 17 is secured to the bottom flanges of the sills 10-10, adjacent the outer ends thereof, the same serving to support the forward end of the yoke of the draft rigging.

My improved draft rigging proper includes broadly a yoke member A; a front follower B; a friction shock absorbing mechanism including a friction shell C and cooperating wedge friction means D and shoes E; combined stop and guide keys F-F; and a saddle plate G.

The yoke A is of the vertical type and has a hooded forward end which receives the shank of the coupler which is indicated by 18. The side walls of the hood are provided with the usual coupler key receiving slots, and a key 19 extending through said slots, the coupler shank, and the slots 14-14, operatively connects the coupler to the yoke. The yoke being of well known form, further description thereof is not necessary.

The shock absorbing mechanism, which includes the friction shell C, and the front main follower B are disposed within the yoke. The front follower cooperates with the shoulders of the front stops 13-13 and bears upon the wedge member D of the friction means.

The friction shell C comprises a spring cage section at the rear thereof and has the friction shell proper formed at the forward end. The shell or casing is provided with a transverse rear end wall 20 which extends laterally outwardly beyond the side walls of the shell and forms the rear follower member of the draft rigging. The rear follower member cooperates with the rear stop casting 15 in the usual manner. The shell or casing C is open at the forward end and has a plurality of friction shoes E slidably movable therein, the shoes having wedging engagement with the wedge block D. The wedge friction means, shoes and shell of the friction shock absorbing mechanism are of well known form and as will be understood, inward movement of the friction shoes therein is resisted by the usual spring means 21.

disposed within the friction shell. The retainer bolt, by which the parts of the friction shock absorbing mechanism are held assembled, is indicated by 22, and as clearly shown in Figure 1, has the rear end thereof anchored to an inwardly projecting hollow boss 123 on the rear end wall of the friction shell. At the rear portion thereof the shell is provided with relatively heavy, laterally projecting lugs or guide members 23-23 on opposite sides thereof. The lugs 23-23 are provided with outwardly opening longitudinal guide ways or slots 24-24 for the purpose hereinafter pointed out. The rear end walls 25 of the guide slots serve as stop shoulders for restricting the forward or draft movement of the friction shell C.

At the forward end the friction shell is supported by the saddle plate G which is secured in any suitable manner to the bottom flanges of the draft sills 10-10. As herein shown, the saddle plate is riveted to the flanges of the sills. In order to properly guide the front end of the friction shell, guide brackets 26-26 are provided on the inner sides of the draft sills. Each of the brackets 26 has a central inwardly offset portion which forms the guide means proper thereof and the brackets are perfectly riveted to the vertical webs of the sills.

The combined stop and guide keys F-F are disposed at opposite sides of the mechanism and are detachably secured to the draft sills 10-10. As most clearly shown in Figure 1, supporting castings 27-27 are provided for the keys F-F. Each supporting casting 27 comprises an elongated plate-like section 28 fixed to the outer side of the corresponding draft sill, and a laterally outwardly extending sleeve-like portion 29 which accommodates a corresponding key F. The plate-like members 28 of the castings are riveted to the vertical webs of the sills 10-10 and have flanges 30-30 at their inner sides 45 which are seated in openings 31-31 provided in the sills 10-10. Each key F is relatively short and is preferably headed at the outer end as indicated at 32. The keys F snugly fit the openings of the sleeve members of the castings 28 and are thus held against movement lengthwise of the sills and are further supported against vertical displacement. The inner ends of the keys F-F are accommodated within the guide slots 24-24 of the lugs on the friction shell, thereby supporting the rear end portion of the shell. In addition to forming supporting means for the shell, the keys F-F also act as fixed stops 50 cooperating with the shoulders formed by the rear walls 25-25 of the guide members of the friction shell C to limit forward or draft movement of the latter. In order to prevent accidental removal of the keys F-F the same are locked in position by bolts 33-33 extending through the top and bottom walls of the

sleeve members 27 and the keys F-F. The bolts are preferably secured by means of cotter pins 34-34 which prevent removal of the nuts from the bolts, due to vibrations of the car in service.

As will be clear upon reference to Figure 1, the compression stroke of the friction shock absorbing mechanism of my improved railway draft rigging is greater in buff than in draft, the normal spacing between the front end of the friction shell C and the front main follower B being greater than the normal spacing between the rear edges of the keys F-F and the shoulders 25-25 formed by the rear end walls of the guide slots of the lugs on the shell.

The operation of my improved railway draft rigging is as follows: Upon inward movement of the coupler in a buffing action the front follower B is thrust rearwardly directly by the butt of the coupler shank, thereby forcing the friction wedge means comprising the wedge D and the friction shoes E-E inwardly of the friction shell C. During this action the shell is held against rearward movement by engagement with the rear stop 15. The inward sliding movement of the friction shoes is yieldingly opposed by the spring means 21. The buffing stroke of the mechanism is limited by engagement of the follower B with the front end of the friction shell C, whereupon the friction shell acts as a solid column to transmit the load to the rear stop of the sills. In this connection it is pointed out that the front follower B is provided with an inwardly projecting central boss 35 which is of such a size as to freely telescope within the open front end of the friction shell C. By this means excessive overhang of the friction web means with respect to the shell is avoided.

In a draft action the coupler is pulled outwardly or to the left as viewed in Figure 1 thereby pulling the yoke in the same direction through the medium of the connecting coupler key 19. In the forward or outward movement of the yoke the friction shell C is pulled outwardly also thereby compressing the friction means against the front follower B which is at this time held stationary by engagement with the front stops 13-13. Outward movement of the shell, in draft, is finally limited by engagement of the shoulders 25-25 of the shell with the rear edges of the keys F-F. The forward or outward movement of the friction shell is thus stopped before the forward end of the shell engages the front follower B.

My improved construction provides for greater compression and greater shock absorbing capacity of the shock absorbing mechanism during a buffing stroke than during the draft stroke thereof. Further, the arrangement of detachable supporting keys facilitates quick application or removal of

the shock absorbing means with respect to the underframe structure of the car. In removing the friction shock absorbing mechanism, the front follower, the yoke and the 5 coupler, it is merely necessary to withdraw the keys F—F and detach the saddle plate G and the carry iron 17. The entire mechanism may then be dropped from between the sills. In the application of the parts the 10 procedure is substantially the reverse, the friction shell being placed between the sills and the keys F—F engaged within the guide slots thereof to support the same.

I have herein shown and described what 15 I now consider the preferred manner of carrying out my invention, but the same is merely illustrative and I contemplate all changes and modifications that come within the scope of the claims appended hereto.

20 I claim:

1. In a railway draft rigging, the combination with a friction shock absorbing mechanism including a friction shell and cooperating friction elements slidable within the 25 shell, said shell having laterally outwardly projecting stop means at the rear end thereof; of a front follower, said shell and follower being relatively movable toward and away from each other, relative approach 30 of the shell and follower being limited in buff by engagement of the former with the latter; and transversely aligned stationary keys secured to the underframe structure of the car, said keys having 35 their inner ends projecting laterally inwardly of the stop means on the shell and having shouldered engagement with said stop means of the shell to restrict the draft movement of the shell to less than the relative movement 40 of the follower and said shell in buff.

2. In a railway draft rigging, the combination with a friction shell having sliding friction means cooperating therewith; of a main follower, said shell and follower being 45 relatively movable with respect to each other; of exterior guideways on opposite sides of the shell, at one end thereof; and transversely aligned, combined supporting and guide keys at opposite sides of the shell, said keys being fixed to the underframe structure of the car and each key having its inner end slidingly engaging within the guideways at the corresponding side of the shell.

55 3. In a railway draft rigging, the combination with spaced draft sills; of front and rear stop means on the sills; a front follower cooperating with said front stop means; a friction shell; rear follower means on the 60 shell cooperating with said rear stop means; wedge friction means slidable within the shell; guide lugs on opposite sides of the shell adjacent the rear end thereof, said lugs having longitudinal guide slots therein; 65 transversely aligned keys removably secured

to the sills, each of said keys having the inner end thereof slidably engaged within the corresponding guide slot to support and guide the shell, said keys being engaged by the inner end walls of the guide slots to limit 70 movement of the friction shell in draft; and means secured to the sills for supporting and guiding the front end of the friction shell.

In witness that I claim the foregoing I have hereunto subscribed my name this 12th 75 day of February, 1931.

JOHN F. O'CONNOR.
